UNITED STATES PATENT OFFICE.

WIRT S. QUIGLEY, OF ROCKAWAY PARK, NEW YORK.

APPARATUS FOR HEATING OVENS.

1,107,353.

Specification of Letters Patent. Patented Aug. 18, 1914.

Application filed October 31, 1912. Serial No. 728,911.

To all whom it may concern:

Be it known that I, WIRT S. QUIGLEY, a citizen of the United States of America, residing at Rockaway Park, county of Queens, 5 State of New York, have invented certain new and useful Improvements in Apparatus for Heating Ovens, of which the following is a specification.

My invention relates to ovens heated internally by hot air, and to furnaces for heating the same. In ovens of this type, as for instance, core baking ovens, the desired temperature is comparatively low, approximately 500 degrees Fahrenheit, as a temperature much above this point will overheat or burn the contents of the oven instead of baking or drying them. On the other hand the temperature of the gases of combustion in an efficient furnace for such an oven will run from 2200° to 2800° Fahrenheit in temperature. If gases at this temperature are led directly into the oven, so as to utilize all the heat generated, the articles nearest the inlet from the furnace are liable to be burned, unless an elaborate system of baffle plates is employed, which waste a portion of the heat, and do not, even then, always remedy the difficulty. This is particularly true of furnaces in which fuel in fluid form is used, either gas, oil or pulverized coal, supplied with air for combustion under pressure, because in such cases the highest efficiency is reached only when the combustible mixture contains about the theoretically correct amount of air for perfect combustion, and any attempt to reduce the temperature by supplying an excess of air at the burner would interfere with the process of combustion. I have overcome this difficulty 40 by supplying air to such furnaces outside of the zone of combustion, to dilute and temper the gases of combustion, thereby conserving the heat, but delivering to the oven a much larger volume of gases at a lower temperature. The efficiency may be further increased by preheating said air of dilution by passing it through passageways formed in the fire brick lining of the furnace before delivering it to the interior thereof.

50 The best form of apparatus embodying my invention at present known to me is illustrated in the accompanying two sheets of drawings in which,

Figure 1 is a cross section of a standard form of core baking oven and furnace therefor with my invention applied thereto, the

section being taken on line 1—1 of Fig. 3; Fig. 2 is a detail section on line 2—2 of Fig. 1 showing the passageways for the air of dilution, and Fig. 3 is a front elevation of the oven, and longitudinal central section of the furnace on line 3—3 of Fig. 1.

Throughout the drawings like reference characters indicate like parts.

1, is the oven chamber having outlet 2, at 65 the top and a series of revolving shelves 3, 3, and partitions 4, 4, so that half of the shelves and articles carried thereon are in the inclosed oven space 1, while the other halves are exposed, so that the previously 70 baked articles may be removed and unbaked articles placed thereon, without interrupting the baking of the articles on the other halves of the shelves. When this is completed, the shelves are given a half turn and 75 the operation repeated. Hot air for the baking operation is supplied from furnace chamber 5, below the oven and communicating therewith through openings 6, 6 in the furnace roof 7. A combustible mixture of 80 air, and gas, oil or pulverized coal is fed to the furnace through inlet 8. In the form illustrated an oil burner 9, is employed.

10, is the combustion chamber, and 11, the bridge wall, or fire back which serves to 85 localize the zone of combustion.

The foregoing constitutes standard construction and would ordinarily be subject in use to the disadvantages above indicated in that the gases would pass up into the oven 90 chamber at nearly the full temperature of combustion, burning the cores or other articles on the lower shelves 3. At the same time the gases would give up so much of their heat to such lower shelves in their slow 95 progress upward that the articles on the top shelves might not be baked sufficiently.

According to my invention I supply a large quantity of additional air to the upper part of furnace chamber 5, outside of 100 the zone of combustion, through openings 12, 12, in the furnace wall. Preferably this air passes through horizontal ducts 13, in the fire brick lining of the furnace, being supplied thereto through passage 14, from 105 blower 15. As shown in Fig. 2, the lower ducts 13, only, are connected to passage 14, and these are connected together and to the upper duct by vertical ducts 16. As shown these ducts are formed in hollow tile constituting the furnace lining.

In operation the proper quantities of fuel

and air of combination to form complete and intense combustion are supplied to the zone of combustion before the bridge wall, but as the highly heated gases so generated 5 pass out into the upper part of the furnace on their way to the oven, they are diluted by air issuing from the openings 12, 12. This air has had its temperature somewhat raised by the heat absorbed from the furnace lining and such heat is delivered to the oven to do useful work instead of being lost in radiator or destructive disintegration of the furnace lining and walls. The 10 quantity of air supplied, however, is so large that its temperature is much less than that of the gases of combustion, and the 15 temperature of the resultant mixture is therefore reduced to a point such that it will not burn even the articles on the lowest of the oven shelves. The quantity of diluted 20 and tempered gases is so great, however, and their velocity of movement through the oven consequently so much greater than the velocity of the gases of combustion alone 25 would be, when no air of dilution is supplied, that said stream of tempered gases retains enough heat even at the point of exit to heat the top shelf in the oven to nearly the same degree as the bottom shelf, 30 thereby producing an equable baking action throughout the oven, without overheating any part thereof. In other words, instead of supplying a hundred cubic feet of gases at 1800 degrees temperature in a given 35 period to the oven, which would burn articles near the inlet but not even bake articles near the outlet, my improved furnace will supply say 300 cubic feet of mixed air and gases, at an initial temperature of some- 40 thing over 500 degrees temperature and which will pass through the oven at three times greater velocity, thus maintaining a baking temperature throughout the oven without overheating any part thereof. An- 45 other advantage is the preservation of the lining and walls of the furnace through the cooling action of the air passing through the hollow tile.

While I have illustrated my invention as 50 applied to the core oven, it is evident that it could be applied with equal advantage to any form of oven heated internally by

the passage of hot gases, and that while I have illustrated an oil burning furnace it would apply equally well to other furnaces 55 burning pulverized fuel or other forms of fuel under a forced blast.

I am aware that heretofore furnaces have been built in which air was admitted to the zone of combustion through passageways built in the wall of the furnace so as to preheat the air, but in all these furnaces the purpose and effect of so admitting air to the zone of combustion was to heighten and complete the combustion which was 65 only partially perfected at the fuel bed. My invention differs from this in that in the furnaces built and operated in accordance therewith, care is taken to so regulate the amount of air supplied to the zone of combustion as to complete said combustion while the additional air supplied outside of the zone of combustion does not combine chemically with the products of combustion but merely dilutes them mechanically, 75 thereby producing a mechanical mixture of much lower temperature for the purposes set forth.

Having, therefore, described my invention, I claim:

The combination with an oven of a furnace having its outlet for gases of combustion connected to said oven, said furnace having a combustion chamber, means for supplying a combustible mixture of air and 80 fuel under pressure to said combustion chamber, a mixing chamber interposed between the combustion chamber and the furnace outlet, the walls of which combustion and mixing chambers have passageways 85 therein discharging into the mixing chamber at points outside of the zone of combustion in the furnace, and means for forcing air through said passageways and outlets, whereby the products of the complete combustion going on in the combustion chamber 90 are diluted with a predetermined quantity of partly preheated air, and the mixture delivered directly to the oven.

WIRT S. QUIGLEY.
